US00D657807S

(12) **United States Design Patent**
Frazier

(10) **Patent No.:** **US D657,807 S**
(45) **Date of Patent:** **** Apr. 17, 2012**

(54) **CONFIGURABLE INSERT FOR A
DOWNHOLE TOOL**

(76) Inventor: **W. Lynn Frazier**, Corpus Christi, TX
(US)

(**) Term: **14 Years**

(21) Appl. No.: **29/398,397**

(22) Filed: **Jul. 29, 2011**

(51) **LOC (9) Cl.** **15-09**

(52) **U.S. Cl.** **D15/139**

(58) **Field of Classification Search** D8/70,
D8/71; D15/21, 138, 139, 140; 166/118,

(57) **CLAIM**

The ornamental design for a configurable insert for a down-hole tool, as shown and described.

DESCRIPTION

FIG. 1 is a perspective view of a configurable insert for a downhole tool;

FIG. 2 is a bottom plan view thereof;

FIG. 3 is a front side plan view thereof, wherein the front side plan view and the back side plan views are identical;

FIG. 4 is a top plan view thereof; and,

FIG. 5 is a left side plan view thereof, wherein the left side plan view and the right side plan views are identical.

The broken lines in the drawings depict unclaimed environmental subject matter.
